I claim the ornamental design for a displaying device for advertisement, as shown and described.

DESCRIPTION

FIG. 1 is a top, front, and right side view of our design for a displaying device for advertisement;

FIG. 2 is a front view thereof;

FIG. 3 is a back side view thereof;

FIG. 4 is a top plan view thereof;

FIG. 5 is a bottom plan view thereof;

FIG. 6 is a right side view thereof;

FIG. 7 is a left side view thereof;

FIG. 8 is a perspective view thereof showing the displaying portion in an alternate position; and,

FIG. 9 is a perspective view thereof showing the displaying portion in an additional alternate position.
